UNITED STATES PATENT OFFICE

147,440

DESIGN FOR A PORTABLE FLUORESCENT
ELECTRIC LANTERN

Harry Harris, Brooklyn, N. Y., assignor to Paramount Industries, Inc., a corporation of New York

Application November 9, 1946, Serial No. 134,672

Term of patent 7 years

(Cl. D48—19)

To all whom it may concern:

Be it known that I, Harry Harris, a citizen of the United States, residing at Brooklyn, in the city of New York, county of Kings, and State of New York, have invented a new, original, and ornamental Design for a Portable Fluorescent Electric Lantern, of which the following is a specification, reference being had to the accompanying drawing, forming part thereof.

The single figure of the drawing is a perspective view of a portable fluorescent electric lantern embodying my new design.

The characteristic features of my design reside in the portions shown by means of full lines in the drawing. The far side of the lamp, not shown in the drawing, is similar to the near side shown in the perspective view. The rear of the lamp is a continuation of the side walls and lies in a plane normal to the side walls.

What is claimed:

The ornamental design for a portable fluorescent electric lantern, substantially as shown and described.

HARRY HARRIS.
